U.S. CL. D7—21

Fig. 1

Fig. 2

Fig. 3

FIG. 1 is a top plan view of a refrigerator dish or the like embodying my new design.

FIG. 2 is a side elevational view, with the opposite side view being identical.

FIG. 3 is an end elevational view, with the opposite end view being identical.

The characteristic feature of the design resides in the particular ornamentation applied to the outer sidewalls, as shown.

I claim:

The ornamental design for a refrigerator dish or the like, as shown and described.
